No. 873,525.

PATENTED DEC. 10, 1907.

J. W. FARNOFF.
GAS BURNER.
APPLICATION FILED OCT. 10, 1906.

UNITED STATES PATENT OFFICE.

JAY W. FARNOFF, OF BUFFALO, NEW YORK, ASSIGNOR, BY MESNE ASSIGNMENTS, TO SHIRLEY M. STOWELL, OF ALDEN, NEW YORK.

GAS-BURNER.

No. 873,525.

Specification of Letters Patent.

Patented Dec. 10, 1907.

Application filed October 10, 1906. Serial No. 338,301.

To all whom it may concern:

Be it known that I, JAY W. FARNOFF, a citizen of the United States, and a resident of Buffalo, in the county of Erie and State of New York, have invented certain new and useful Improvements in Gas-Burners, of which the following is a specification.

My invention relates to gas-burners, and more particularly to pressure regulating valves therefor.

The objects of this invention are, the production of a regulating-valve of simple construction which can be cheaply manufactured and wherein provision is made to positively retain the valve in any adjusted position; to so construct the valve that it can be quickly and conveniently regulated and whereby leakage of gas between the casing and the actuating-spindle is prevented.

To these ends, the invention consists in the construction, arrangement, and combination of parts to be hereinafter described and particularly pointed out in the subjoined claims.

In the accompanying drawings,—Figure 1 is an elevation of a complete burner applied to a fixture for use. Fig. 2 is a vertical section of the bunsen or mixing tube, its attached gas regulating-valve, and the mantle-support, taken on line $x-x$ Fig. 1. Fig. 3 is an enlarged vertical section of the gas regulating-valve, taken on line $y-y$, Fig. 2. Fig. 4 is an enlarged cross-section taken on line $z-z$, Fig. 1. Fig. 5 is a detached perspective view of the tension-spring by means of which the regulating-valve is maintained in any adjusted position. Fig. 6 is a detached perspective view of the removable taper tube within the bunsen or mixing tube.

Referring now to the drawings in detail, corresponding numerals of reference refer to corresponding parts throughout the several figures.

The reference numeral 1 designates the gas fixture through which the gas is fed to the burner; it being provided with the usual cock 2 by means of which the supply of gas is shut off or turned on. This fixture may be of any design or form to permit of connecting the burner in position.

3 designates the bunsen or mixing-tube, 4 the gas regulating-valve, 5 the combined mantle-support and diffuser, and 6 the mantle held to said support. Said mixing-tube is internally threaded at its upper end to receive the threaded portion 7 of the gas regu-

lating-valve, and near its upper end has air apertures 8 adapted to be opened to any desired extent to govern the admission of air to the mixing tube by a shutter 9 fitting around the upper end of the mixing tube and arranged for rotation thereon. Said shutter is of somewhat larger diameter than the mixing tube and centrally has a vertical sleeve 10 fitting said tube snugly, and provided with air-apertures 11 corresponding in number and preferably in size to the air-apertures in said tube. Said shutter is held in position on the mixing-tube by a shoulder 12 formed on the latter against which the shutter bears.

The bore of the mixing-tube is cylindrical at both ends, but somewhat smaller in diameter at its lower end than at its upper end, and the intermediate portion is tapered downwardly, as at 13, to connect the cylindrical ends by a gradual restriction. Fitting into said tube is a removable tapered-tube 14 having the same degree of taper as the intermediate portion of said mixing tube and extending down into the latter to a point even with or almost even with the lower end thereof. Tube 14 is tapered throughout its length and by reason thereof, is separated at its lower end from the wall of the mixing tube 3 by an annular space 15 gradually restricted upward to a point where tube 14 is in contact with the tapered portion of the bore in the mixing tube. Said tapered tube serves to compress the commingling gas and air, and causes the gas to pass therefrom under higher pressure, which is highly essential when burning artificial gas, usually under considerable lower pressure than natural gas. It is apparent therefore, that by the use of said tapered tube, the pressure of the gas is increased previous to issuing from the mixing tube, and burns with a blue flame. This tapering tube also avoids back-flashing, prevents flickering of the light, and carbonizing; due to the fact that the gas entering the mixing tube under low and uneven pressure issues therefrom under increased and constant pressure. When burning natural gas or any other gas under a high and constant pressure, the tube 14 is removed.

The lower end of the mixing tube is provided with an external threaded collar 16 engaged by the internal thread of the diffusing chamber 5 which has a depending tube 17 provided with a plurality of lugs 18 to be engaged by the mantle holder 20 to which the

mantle is affixed. Within said diffusing chamber is a removable wire diffuser 19 through which the gas issuing from the mixing tube passes prior to being ignited. This 5 diffuser, has been found by experiment to be very advantageous when using a low pressure gas, but when burning a high-pressure gas, it also may be omitted. Midway between its ends the mixing-tube has externally 10 a collar 20^a and a plurality of upwardly tapering lugs 21.

The globe-holder, designated 22, fits onto the mixing-tube and is held in frictional contact with said lugs to prevent turning or 15 wabbling, while collar 20^a supports said globe-holder. Passing through said globe-holder are fastening-screws by means of which the globe 24 is fastened to said holder. The globe-holder and means of fastening the 20 globe thereto may be varied, as it forms no part of my invention. The globe 24 is closed at its lower end, as at 25, and while the body or main portion may be of any shape or outline desired, I preferably enlarge the lower 25 end beyond the adjacent portion of the body, as at 26, to form an internal restriction or bead 27, and in said enlarged lower end, a plurality of air-apertures 28 are formed through which the air is admitted to the interior 30 of the globe. In this manner accidents, caused by particles of the mantle falling when accidentally jarred, are guarded against, and the direct inrush of air to the mantle is also prevented by reason of the restricted portion deflecting the air-currents to 35 the sides of the mantle.

The regulating-valve casing has its lower end made conical, as at 29, and projects into the upper end of the mixing-tube so that its 40 lower extremity terminates beneath the air-apertures in said tube, thus causing the air to be drawn into said tube by the gas issuing from said valve-casing. Within the valve-casing is a needle-valve 30 adapted to be adjusted with reference to the gradually restricted portion 31 of the bore 32 of said casing, and thus regulate the supply of gas to 45 the mixing-tube. Said needle-valve has enlarged longitudinally grooved portions 33 which bear against the interior of the valve-casing and guide the valve for vertical movement while permitting the gas to pass 50 through said casing. Between said longitudinally grooved portions, a cylindrical por-

tion 34 is formed in which is machined a circumferential groove 35 adapted to receive the crank-pin or eccentric stud 36 of an actuating spindle 37 fitting into an opening 38 in the valve-casing. Said opening has a concaved portion 39, into which is seated the correspondingly shaped enlargement 40 on said spindle to form a gas-tight joint and prevent leakage of gas through said opening; said enlargement having an annular groove 41 into which fits the lower end of a retainer and tension spring 42 that has at its upper end an inwardly directed portion 43 bearing against the valve-casing. Said spring has its lower end bifurcated, as shown in Fig. 5, to straddle the actuating spindle and between its 60 ends has an aperture 44 through which is passed a screw 45 that enters a threaded bore in the valve-casing. By loosening or tightening said screw, the tension of the spring may be regulated to seat the enlarged portion of the spindle firmly against its seat, and to maintain said spindle in any adjusted position.

It is apparent from the foregoing, that upon rotating the actuating spindle, which 65 has a milled head 46 to conveniently manipulate the same, the needle-valve is raised or lowered to the position desired.

Having thus described my invention, what I claim is,—

In a gas-burner, a valve-casing having a chamber and an opening in its side, a vertically movable valve in said chamber provided with a circumferential groove, an actuating-spindle passing through said opening in 70 the casing and having an eccentric stud entering the circumferential groove in said valve, said spindle having an annular groove in its projecting portion and a retainer having a lip at one end bearing against the valve-casing, a bifurcated portion at its other end fitting the annular groove in said spindle, and a fastening screw passing therethrough 75 between its ends and entering the valve-casing.

In testimony whereof, I have affixed my 80 signature in the presence of two subscribing witnesses.

JAY W. FARNOFF.
